CLOSURE FOR BOTTLES AND OTHER CONTAINERS

Gilbert Jackson, New York, N. Y.

Application November 14, 1933, Serial No. 697,892

2 Claims. (Cl. 215—22)

My invention relates to closures and it particularly relates to non-refillable closures for bottles and similar liquid containing receptacles.

In my Patent No. 1,348,116, dated July 27, 1920, I have disclosed a non-refillable bottle closure or cap which had for its object the preventing of the refilling of bottles after they had been emptied.

In said patent there was disclosed a hollow valve member which cooperated with a cylindrical valve seat inserted in the mouth of the bottle. Above the valve and the valve seat was positioned a movable ball. The ball was confined between the valve member on one side, and at the other side contacted with a concave contact member.

As disclosed in said patent, the valve member was preferably of a porous material. This porous material was of such a nature that the valve, when wet, would attach itself firmly to its seat when the bottle was upright and yet not prevent said valve leaving its seat, when the bottle was inverted.

An object of the present invention is to provide a non-refillable bottle closure of the type, as above described, in which the valve member and its associated parts would be constructed of non-porous material and in which the various parts of the structure may be most inexpensively and easily constructed from readily available materials, as for example, plastics such as bakelite.

Another object is to provide a non-refillable bottle closure of the type above described in which the closure is positively effected and the valve is forced positively to its seat when the bottle is not in inverted discharging position.

Other objects will appear during the course of the following specification.

In accomplishing the objects of the present invention it has been found most suitable in one embodiment to provide a valve casing having an upper closure, exteriorly exposed, and a lower opening to communicate with the interior of the container or bottle.

The lower portion of the valve casing may be of a decreased diameter so as to fit conveniently into the neck of the bottle, a shoulder being preferably provided on the casing to limit insertion thereof.

Interiorly positioned in the valve casing is a valve member preferably of hollow construction, the lower end of which valve member is formed so as to cooperate with a valve seat interiorly formed in the bottom of the casing adjacent the interior opening thereof above described.

In the upper part of said casing is preferably provided a ball which cooperates with a concaved

member in the upper part of the casing and with a conical or other domed portion at the top of the movable valve.

In the accompanying drawing in which is shown one or more of various possible embodiments of the several features of the invention,

Fig. 1 is a longitudinal cross sectional view of the non-refillable sealing device of my invention.

Fig. 2 is a transverse sectional view upon the line 2—2 of Fig. 1.

Fig. 3 is a transverse sectional view upon the line 3—3 of Fig. 1.

Figs. 4, 5 and 6 are perspective views of the various elements of my construction removed from the assembly in Fig. 1.

Referring to Fig. 1, the bottle or other container B is provided with a cylindrical mouth 10. The bottle is adapted to receive alcoholic beverages or any other liquid to be dispensed.

The cylindrical valve casing 12 is provided with an insert portion 13 of reduced diameter, which is inserted in the opening 14 in the mouth or neck of the bottle B and is stopped by the shoulder 15 on the upper rim 16 of the mouth of the bottle 10.

The insert portion 13 is provided with a peripheral groove 52 adjacent its lower end. The casing 12 is provided with a lower opening 17, the upper part of which is provided with the spherical depression 19, said depression 19 serving as a valve seat to cooperate with the spherical surface 20 on the valve member 21.

The valve member 21, as shown in Figs. 1, 3 and 6, has a cylindrical hollow cup-shaped body 22, exteriorly provided with symmetrically spaced fins 23. The fins 23 centrally locate the valve 21 within the lower chamber 24 of the casing 12.

The lower part of the valve member 21, as indicated at 25, projects downwardly past the conical valve seat 19 into the opening 17 (see Fig. 1).

The lower portions of the fins are steeply bevelled, as indicated at 27 (see Figs. 1 and 6), so that they will clear the valve seat 19.

As shown in Fig. 3, the fins 23 space the cylindrical body 22 from the walls of the lower chamber 24 of the casing 12 with the formation of the flow passage 28, which permit ready egress of liquid from the mouth 10 of the bottle B past the valve body 21, when the valve is lifted from its seat 19.

The top 29 of the valve body 22, as shown in Figs. 1 and 6, is flattened and into the upper portion of the cup 22 is inserted the lower contact element 30 for the locking ball 31.

The contact element 30 is provided with a main disk 31, the lower face of which contacts

with the upper flattened face 29 of the valve member 21. From the side of the disk member 31 extend the fins 32, which are preferably positioned directly above and in alignment with the fins 23, so as to continue the flow passage 28 past the structure 30. From the lower part of the disk 31 projects the nipple insert 33, which fits into the upper part of the cup opening 34 of the valve body 22.

10 When the contact member 30 is pressed into position, a body of air will be confined in the interior of the cup 34 under a slight pressure. The upper part of the ball contact member 30 is suitably domed to cause the ball 31, as shown in Fig. 1, to roll outwardly of the casing 12 against the interior wall of the middle or intermediate chamber 35 when the bottle is upright.

In the present invention a conical dome 36 is shown, but it is understood that any other type of dome structure may be employed for causing the ball to roll toward the wall of the middle chamber 35 of the casing 12.

As shown in Figs. 1, 2 and 4 into the upper chamber 37 of the casing 12 is inserted the concave ball contact member 38, the symmetrically positioned fins 39 of which rest upon the shoulder 40 at the bottom of said chamber 37.

The concavity or depression 40 of the element 38, as shown in Fig. 1, is adapted to receive the ball 31 when the casing 12 is inverted with the bottle 10.

When the bottle is in normal upright position, as shown in Fig. 1, the ball 31 will be diverted to the outside of the chamber 35 by the cone 36 so that the ball 31 will wedge between the edge 41 of the upper contact member of the cone 36 of the lower contact member 30, as indicated in Fig. 1.

As indicated in Fig. 2, the fins 39 will form the flow passages 42, symmetrically positioned around the periphery of the chamber 37. These flow passages 42 will cooperate with the flow passages 28 to permit liquid to flow past the valve 21 and the concave contact member 38.

45 From the main body 43 of the concave member 38, extend upwardly the arcuate fins 44, provided with notches 45. These fins 44 contact with the upper closure member 46 having a portion 47 of reduced diameter inserted into the upper portion of the chamber 37 and provided with a shoulder 48 contacting with the top 49 of the casing 12.

The closure element 46 is provided with a center opening 50 which cooperates with the passages 42 past the concave contact member 38 and the passages 28 past the valve member 21 and with the opening 17 in the lower part of the casing 12, whereby liquid may be poured out of the inverted bottle 10, when the valve 21 is lifted from its seat 19.

In operation, when the bottle is in upright position or is in horizontal position, the ball 31 will slide or roll over the cone 36 to the side of the chamber 35, contacting with the interior walls thereof, as indicated in Fig. 1.

When the ball 31 moves to the side of the chamber 35, it will wedge between the outer lower portion of the upper concave contact member 38 and the lower domed contact member 30 and will force the valve 22 against its seat 19, preventing flow of liquid reversely from the opening 50 and through the opening 17 into the bottle 10, so that the bottle cannot be refilled.

When the bottle has been turned so that its mouth is inclined downwardly with an inclina-

tion substantially below horizontal, approaching the vertical inverted position, the ball 31 will roll or slide into the concavity 40. This will permit the valve 22 to move from its seat 19 under the pressure of liquid in the bottle 10, whereby a ready exit of liquor may take place through the opening 17, the passages 28 and 42 and the opening 50.

The upper face of the lower ball contact member 30 may also be domed to conform with the concave concavity of the depression 40. In any case, at the axis of the combination at 51, there would be a vertical spacing between the uppermost portion of the dome 36 and the uppermost portion of the dome 40 which will be greater than the maximum diameter of the ball. Toward the walls of the chamber 35 this spacing should decrease so that the ball will wedge or jam as it moves under the influence of gravity along the domed surface 36 toward the exterior of the chamber 35 and away from the axis 51.

It is also evident that the surface 41 may also be of cone-shape, instead of dished, as shown, similar to the cone 36 with the sloping faces of the dome 36 and the concavity 40 converging as they depart from the axis 51.

The air space 34 inside of the valve member 21 may be advantageous in certain connections. If a vacuum is applied to the closure 46, such vacuum will result in the air, compressed in the cup 34, expanding and pressing the element 30 upwardly to jam the ball 31 between the dome 36 and the concavity 40.

The entire structure shown may be formed of Bakelite parts or of other molded or shaped plastic materials. It is also possible to make the structure of other materials, for example, the ball being most satisfactorily of a hard glass.

It will be noted that no matter how much the device is shaken or joggled when in upright position the bottle will not be open for refilling. It is not possible to insert any element through the opening 50 which will permit opening of the valve 22. It may be noted that there is no direct passage for the insertion of a pin or similar element from the opening 50 into the chamber 35 for moving the ball back toward the axis 51 of the structure, since the passageways 42 communicate with the space inside of the fins 44. It is necessary for the liquid flowing to the opening 50 from the chamber 35 to flow first to the side of the passages 42 before entering the passages 42 in passing across the main body 43 of the upper contact member 38.

The present construction is particularly advantageous inasmuch as it is not necessary to make the valve member 21 of a non-porous material. By inserting the upper contact element 38 in position in the manner shown without threading the exterior thereof, the expense of construction is materially decreased. The provision of four flow passages 28 past the valve casing 21, and three flow passages 42 past the upper contact member 38 assures a more even and better exit of liquid when the bottle is inverted for dispensing purposes.

Where it is not desired to utilize the air in the cup 34 the valve member 21 may be made of solid construction, but it preferably is of such construction that it should float in liquid and be non-porous so as not to saturate itself with the liquid contained in the bottle or dispensed thereby.

What is claimed is:

1. In a non-refillable closure for liquid containing bottles and similar receptacles, a main

casing provided with a nipple portion of decreased diameter to be inserted into the top of the container with a shoulder with the top of said portion of decreased diameter to contact with the top of the bottle and limit the insertion of the cylindrical member, said casing being provided with three chambers of increasing diameter upwardly, the lower chamber being provided with a central axial opening into the bottle and the upper chamber being provided with an annular closure, the lower chamber receiving a hollow cylindrical valve member, the center chamber receiving a ball and the upper chamber receiving an upper contact member, the valve member being provided at its lower end with a conical face cooperating with a conical valve seat in the lower part of the lowermost chamber of said casing, and at its upper end with a conical structure for contact with the ball in the center chamber and causing it to move toward the exterior of said center compartment and the upper contact member being provided with a center concavity for receiving said ball when the bottle is in inverted position, whereby said valve may be removed from said valve seat by gravity and the pressure of the liquid

in the bottle, said valve member and said upper contact member being provided with a plurality of fins to form flow passages in the upper and lower chambers permitting free egress of liquid when said bottle is in inverted position.

2. In a non-refillable closure for bottles and other containers, a main casing provided with three chambers of increasing diameter upwardly, the lower chamber receiving a hollow cylindrical valve member, the center chamber receiving a ball and the upper chamber receiving an upper contact member, the valve member being provided with a bottom valve portion cooperating with a valve seat in the lower part of the lower chamber of said casing, the upper portion of said valve being provided with a dome structure for contact with the ball in the center compartment to cause it to move toward the exterior of said center compartment and the upper contact member being provided with a central depression for receiving said ball when the bottle is in an inverted position, whereby said valve may be removed from said valve by gravity and the weight of the liquid in the bottle.

GILBERT JACKSON. 25
